J. S. DUNCAN,
PLATEN FOR ADDRESS PRINTERS,
APPLICATION FILED SEPT. 18, 1914.

1,186,758..

Patented June 13, 1916.

UNITED STATES PATENT OFFICE.

JOSEPH S. DUNCAN, OF CHICAGO, ILLINOIS, ASSIGNOR TO ADDRESSOGRAPH COMPANY,
OF CHICAGO, ILLINOIS, A CORPORATION OF ILLINOIS.

PLATEN FOR ADDRESS-PRINTERS.

1,186,758.

Specification of Letters Patent. Patented June 13, 1916.

Application filed September 18, 1914. Serial No. 862,271.

To all whom it may concern:

Be it known that I, JOSEPH S. DUNCAN, a citizen of the United States, residing at Chicago, in the county of Cook and State 5 of Illinois, have invented new and useful Improvements in Platens for Address-Printers, of which the following is a specification.

The object of this invention is to provide 10 means which can be easily and quickly operated to produce a printing impression from any selected portion of a form and more particularly to enable impressions to be taken from the whole or certain lines of a 15 printing form as may be desired.

The invention is more especially adapted 20 for address printers of that class which embody reciprocating platens to produce impressions from the type forms, usually addressed, of printing devices which are adapted to be arranged in accordance with a card index system.

It is sometimes desired to take an impression 25 of the entire address and separate impressions of the name on the first line and the street and city on the second and third lines or other combinations as may be found useful. I have found this can be conveniently accomplished by providing a sectional 30 platen with means for relatively adjusting the sections as required to project into operative position for obtaining the desired impression.

In the accompanying drawings illustrating 35 one embodiment of the invention Figure 1 is a sectional view showing a reciprocating platen arm and platen of an address printer with a printing device in printing position. Fig. 2 is a front elevation of the 40 platen and front end of the platen arm. Fig. 3 is a sectional view on the line 3—3 of Fig. 2. Fig. 4 is an end view of the platen.

Referring to the drawings, 5 is the bed 45 of the machine upon which the printing device 6 rests during the impression operation, these printing devices being placed in printing position by hand or automatically fed thereto from a magazine 7 in a 50 suitable manner. The platen arm 8 is pivotally mounted at 9 on the frame of the machine and is preferably provided with a handle 10 conveniently located for depressing the platen arm. This platen arm 55 is preferably returned to and normally held

in the elevated position shown in Fig. 1 by a spring (not shown).

The platen illustrated in the drawings comprises two sections 11, 12 which are arranged for relative movement in the head 60 13 secured on the platen arm by a bolt 14 which extends through an enlarged opening 14' of said arm. The platen is adjusted lengthwise by screws 15 which extend through the arm and bear upon the head on 65 opposite sides of the bolt 14 and the platen is adjusted transversely by a screw 16 which passes through the arm and bears upon a lug 16' extending rearwardly from the head. The head has two parallel channels 17 extending lengthwise thereof to accommodate the sections and the latter are held in place in the channels by transverse bolts 18 which pass through slots 19 in the sections. Springs 20 are interposed in said 70 slots between the bolts 18 and the upper ends of the slots to normally sustain the sections in elevated position. Cam-face rods 21 are located in the upper ends of the channels 17 above the sections to operate on the 75 sections and depress the same when turned to proper position and for this purpose crank handles 22 are provided on the rods to work between stops 23 on the end of the head.

In the embodiment of the invention selected for illustration here the platen is made in two sections, one of which has a T-shaped head 11' adapted to produce an impression from two lines of type on the printing device, and the other of which has an L-shaped head 12' adapted to produce an impression from one line of type on the printing device, but it will be readily understood that the platen may be divided into 90 more sections of different shapes as occasion may require. When it is desired to take an impression from the entire printing device the sections will be arranged with their faces flush as shown in the drawings. 100 To take an impression from, say, the first or name line of the address the cam rod for section 11 will be adjusted to permit the springs 20 to move this section upward until its face 11' is above (or back from) the 105 plane of the face 12' of the other section so that in the next operation of the platen arm the section face 12' will be carried into operative relation to the name line of the printing device while the face 11' of the other 110

section will be held out of operative relation with the printing device. To obtain an impression from the street and city lines of the printing device the cam rods will be operated to adjust the platen face 11' in operative relation and the platen face 12' out of operative relation with the printing device. These adjustments can be very easily and quickly effected without any material interruption in the speed of the machine so that successive printing operations may be performed to take an impression from the entire printing device and then from parts of the printing device by properly manipulating the cam rods. It will be understood, of course, that these printing devices may be provided with forms for printing other subject matter than an address and that the sections of the platen may be arranged and constructed in such form and numbers to produce any combination of impressions from the printing device that may be desired.

1 claim:

- 25 1. In a printing machine, the combination of a support, and a platen supported thereby and bodily movable therewith, comprising a head and a pair of parallel sections slidably mounted thereon and having their faces, normally located in the same plane, and means for adjusting said sections relatively and independently to move one or the other of said faces out of operative position.
- 30 2. In a printing machine, the combination of a support, and a platen supported thereby and bodily movable therewith, comprising a head having a plurality of channels therein, a platen section movably secured in each of said channels, and means for relatively adjusting said sections.
- 35 3. In a printing machine, the combination of a support, and a platen supported

thereby and bodily movable therewith, comprising a head, a plurality of platen sections secured therein, springs normally acting on said sections to hold them in position with their faces in the same plane, and independent means operatively associated with said sections for moving them relatively in and out of operative position.

4. In a printing machine, the combination of a support, and a platen supported thereby and bodily movable therewith, comprising a head provided with a plurality of channels, a platen section mounted in each of said channels, means for normally holding said sections in position with their faces flush, and cam devices operating upon the platens for depressing one relatively to the other.

5. The combination of a head, a plurality of slotted platen sections movably arranged in said head, bolts passing through the walls of the head and the slots in the platen sections, springs located in the slots between the bolts and the upper ends of said slots to normally hold the platen sections in elevated position with their faces in the same plane, and means within the head for operating upon said platen sections to adjust said sections relatively and independently.

6. The combination of a platen arm, a platen head, a platen carried by said head, a bolt loosely mounted in said head for securing said head to the arm, adjusting screws operating through the arm on the head on opposite sides of said bolt, a lug projecting rearwardly from the head, and an adjusting screw operating through the head upon said lug behind the bolt.

JOSEPH S. DUNCAN.
